UNITED STATES PATENT OFFICE.

GEORGE H. PAPPAS, OF BALTIMORE, MARYLAND.

DESIGN FOR CANDY.

59,863.

Specification for Design.

Patented Nov. 29, 1921.

Application filed April 19, 1921. Serial No. 462,720. Term of patent 14 years.

To all whom it may concern:

Be it known that I, GEORGE H. PAPPAS, a subject of the King of Greece, residing at Baltimore, in the county of Baltimore and State of Maryland, have invented a new, original, and ornamental Design for Candy, of which the following is a specification, reference being had to the accompanying drawing forming part thereof.

Fig. 2 is a vertical sectional view taken through the end portion of the raised arm.

I claim:

The ornamental design for candy as shown.

GEORGE H. PAPPAS.
